UNITED STATES PATENT OFFICE.

WILBUR F. OSBORNE, OF ANSONIA, CONNECTICUT.

DESIGN FOR A SUSPENDER-STRAP.

SPECIFICATION forming part of Design No. 17,347, dated May 17, 1887.

Application filed April 13, 1887. Serial No. 234,702. Term of patent 3½ years.

To all whom it may concern:

Be it known that I, WILBUR F. OSBORNE, a citizen of the United States, residing at Ansonia, in the county of New Haven and State 5 of Connecticut, have invented and produced a new and original Design for Suspender-Straps, of which the following is a specification.

This design has for its object to provide a 10 novel suspender-strap; and it consists in a suspender-strap having the longitudinal edges of one face provided with separated dots and the longitudinal central body of the opposite face provided with separated dots, all of said 15 dots being of a color contrasting with the color of the body of the strap.

The design is illustrated by the accompanying drawings, in which—

Figure 1 is a plan view of part of a suspender-strap, showing the face having the 20 dotted center; and Fig. 2, a similar view showing the opposite face of the strap.

In the drawings, the numeral 1 indicates the longitudinal central body of part of a sus-

25 pender-strap, and 2 the longitudinal edges thereof. The longitudinal center is provided on one face with separated dots 3, shown as alternating, and the longitudinal edges of the opposite face are each provided with separated dots 4, all of such dots being of a color contrasting with the color of the body of the strap. The dots on the edges are also shown 30 as alternating.

Having thus described my invention, what 35 I claim is—

The design for a suspender-strap having the dotted longitudinal central body on one face and the dotted longitudinal edges on the other face, all of the dots being of a color contrasting with the color of the body of the strap, 40 substantially as shown and described.

In testimony whereof I affix my signature in presence of two witnesses.

WILBUR F. OSBORNE.
